UNITED STATES PATENT OFFICE.

JAMES H. RAND, JR., OF TONAWANDA, NEW YORK.

INDEX DEVICE.

Application filed January 6, 1923. Serial No. 810,970.

This invention relates to improvements in index or record devices.

Heretofore index or record devices comprising cards or card-holders having parts 5 or means for attachment to a support have been provided. These cards or card-holders have been adapted to be arranged in overlapping order or arranged with the margins of the several cards or holders exposed one 10 above another. The cards or card-holders have been scored or creased transversely so that a portion of or the body of the card or holder may be swung upwardly to permit data on the lower cards or card holders to be 15 examined or entries to be made thereon or to permit the cards to swing upwardly and be thrown back so that entries may be made on the backs of the cards or the like. This scoring or creasing which in effect results in 20 the hinging of one portion of the card or holder to another portion of the card or holder, has in some instances been provided along two parallel lines, intending that when the card is swung on this hinge the card or 25 holder would bend at the two parallel lines of scoring or creasing. The scoring or indenting of the material compresses the fibers of the material adjacent the indentations, thereby rendering the fibers more likely to 30 be broken when the material is bent along the scored lines and also by forcing the fibers aside tends to release the bond between the fibers. It has been found in practice that as a rule the material of the cards is 35 bent only along the weaker one of the two scored or creased lines. This results in a very abrupt bending of the material of the card and while the cards or card holders are usually constructed of relatively tough 40 paper or material, in use, repeated abrupt bending or folding of the card or card holder results in fracture of the fibers of the material along the lines on which it is bent and the portions of the cards or card-holders 45 become torn or severed one from the other.

The objects of the present invention are to provide a record or index card or card-holder having a part which is hinged relatively to another part thereof in such manner that the hinged portion may be readily manipulated without any likelihood of breaking or tearing the material thereof; also to provide a card or card-holder having an improved hinge connection between 55 parts thereof whereby the hinged portion may be more easily moved to its several posi-

tions; and also to provide improvements in record or index card holders or cards in the other respects hereinafter set forth and claimed.

In the accompanying drawings:—

Fig. 1 is a plan view of a card-holder embodying the invention, the card therein being partly broken away to disclose the underlying portion of the holder.

Fig. 2 is a transverse section thereof with the body of the card-holder thrown back on its hinge joint.

Fig. 3 is a perspective view of a record or index card embodying the invention.

Fig. 4 is a fragmentary sectional perspective view of one corner of the card-holder with the parts as in Fig. 2.

Fig. 5 is a cross section of the card shown in Fig. 3 on line 5—5, Fig. 3.

Fig. 6 is a fragmentary sectional perspective view of the lower portion of a card and its holder showing the same turned back to expose the rear face of the card.

The invention, generally stated, comprises 80 a card or card-holder for receiving record or index data or matter, having a flexible portion or part connecting portions of the card or holder. The flexible portion is preferably formed integrally with the several 85 portions of the card or holder which it connects and is of sufficient size so that in use it will be flexed or bent on curved lines, avoiding any sharp, abrupt bending which might tend to fracture or break the material 90 of the card.

In Fig. 1 there is illustrated a card A provided with side projections or tongues B which are adapted to be inserted beneath the flanges of a record tray and whereby the 95 cards are maintained in position. This card is of the type adapted to have index or record data imposed directly on it or to support a separate card or slip on which the index or record data appears.

The upper and lower portions of the card are connected by means of a flexible portion comprising preferably a plurality of flexible parts or connectors 10. This flexible portion, or as shown in the embodiment of 105 the invention illustrated, these flexible connectors 10 are preferably formed of integral portions of the material forming the card, as by providing a plurality of apertures or openings 11 in the card. In order to provide 110 a relatively true hinge, the apertures or openings 11 and the connectors 10 therebe-

tween are formed in substantial alinement transversely of the card. The flexible connectors 10 are of sufficient length in a direction from the top to the bottom of the card 5 to permit their bending on curved lines as indicated in Fig. 2. The connectors 10 may be readily formed in the card by a simple stamping operation; they are, therefore, very economical to produce and by reason 10 of the fact that there is no abrupt bending, folding or creasing of the material from which the card is made, the card and the hinge are long lived.

In Fig. 3 the invention is applied to a 15 card having means for attachment to a support and in which the hinge is formed in the body of the card. In Fig. 3, D designates a record or index card having tongues or projections E for attachment to the usual 20 support, and like the card shown in Fig. 1, having connectors 10^a separated by spaced openings 11^a formed therein in the manner specified for the device shown in Fig. 1.

As illustrated in Figs. 1 and 6, the device 25 may be provided with a hinge or flexible portion of the type disclosed hereinabove, adjacent the lower part of the card or holder. This lower hinge permits of the lower 30 portion of the card or holder being turned under as shown in Fig. 6, so that the reverse side of a card C in the sheath or pocket S may be examined or have entries made thereon without removing the card from the pocket. As in the case of the hinge 35 connector hereinabove described, this lower hinge preferably consists of a flexible portion formed by a plurality of flexible parts or connectors 12. These parts are preferably formed of integral portions of the material forming the card or holder as by providing a plurality of apertures or openings 40 13 in the card or holder. The provision of this improved hinge at the bottom portion of the holder as well as at the top, facilitates a ready swinging or throwing backwardly of any holder or holders to permit 45 an examination of or operation upon a card or holder therebeneath and at the same time permits of ready inversion of a card on said

holder so that both sides of the card on 50 the face of the holder may be used for record purposes without the necessity of removing the card from the holder.

In the accompanying claims, the word 55 "card" is used to designate a card upon which index or record matter is directly written or imposed, or a holder adapted to support another member having record or index matter appearing on it, such for example as a separate card or slip. 60

I claim as my invention:—

1. In an index or record device, a holder 65 having means for attachment to a support and means adjacent one edge thereof for releasably holding a card or slip, a hinge in said holder adjacent said releasable holding means for permitting said card or slip to be inverted without detaching it from said holding means, said hinge including a plurality of alined spaced flexible parts. 70

2. In an index or record device, a holder 75 having parts adapted to be attached to a support, a hinge in said holder adjacent said attaching portion, means adjacent a portion of said holder relatively remote from said attaching portion for releasably securing a card or slip on said holder, said holder being provided adjacent said card-securing means with a plurality of spaced flexible parts constituting a hinge and permitting 80 a portion of said holder to swing relatively to the other portions of said holder to invert said card or slip. 85

3. In an index or record device, a holder 90 having means for attachment to a support, said holder having a plurality of spaced flexible hinge portions, said hinge portions being integral with said holder and of greater flexibility than the remaining portions of said holder, and spaced apart to 95 permit portions of said holder to be swung in reverse directions, to permit an examination of a holder or index member or members below said holder or to permit a card or index member on said holder to be inverted without removing it from said holder.

JAMES H. RAND, JR.
